Primary Examiner — Angela J Lee(74) *Attorney, Agent, or Firm* — Justin Cassell; Workman Nydegger(57) **CLAIM**

The ornamental design for a tail light assembly, as shown and described.

DESCRIPTION

FIG. 1 is a perspective view of a tail light assembly showing the design;

FIG. 2 is a front elevational view of the tail light assembly of FIG. 1;

FIG. 3 is a back elevational view of the tail light assembly of FIG. 1;

FIG. 4 is a top plan view of the tail light assembly of FIG. 1;

FIG. 5 is a bottom plan view of the tail light assembly of FIG. 1;

FIG. 6 is left side elevational view of the tail light assembly of FIG. 1; and,

FIG. 7 is a right side elevational view of the tail light assembly of FIG. 1.

The dash-dash broken lines showing environment in the drawings are included for illustrative purposes only and form no part of the claimed design. The dot-dash-dot broken lines shown in the drawings define the boundaries of the claim and form no part thereof.

1 Claim, 4 Drawing Sheets(56)
